REGISTER CONTROL MECHANISM

William C. De Reo, Holland, Mich., assignor to
 Hart & Cooley Manufacturing Co., Holland,
 Mich., a corporation of Delaware

Application February 28, 1952, Serial No. 273,839

5 Claims. (Cl. 268—1)

1
 This invention relates in general to dampers or registers of the character wherein adjacent vanes or louvers rotate in relatively opposite directions between the open and closed positions thereof and is more particularly directed to a novel form of control mechanism for operating the louvers.

It has been recognized for some time that registers wherein the cooperating louvers rotate in relatively opposite directions from the closed to open positions have the advantage of directing the air flow in a more generally upward direction therethrough than where all of the louvers rotate in the same direction. In the latter case when the louvers, which are generally caused to move simultaneously, are partially opened, the air flow will be given a more angular direction upwardly when the louvers are only partially opened, whereas in the case of louvers rotating in relatively opposite directions, the air flow will be directly in an upward direction regardless of the angle through which the louvers have been rotated.

One of the problems which has been presented in connection with the oppositely rotating adjacent louvers is the provision of a simple and inexpensive mechanism for initially moving the leading edge of one of the louvers at a greater angular velocity than the trailing edge of the adjacent louver. In order to effectively close the register to prevent dust and dirt as well as heat from being conducted therethrough, it is necessary that adjacent louvers overlap at their adjacent edges. Where adjacent louvers rotate in the same direction there is no problem involved in moving the louvers to open position because the adjacent edges thereof will be moved in opposite directions.

It is, therefore, a principal object of the present invention to provide a simplified and economic mechanism for properly controlling the rotating movements of adjacent louvers in a register where adjacent or alternate louvers rotate in relatively opposite directions.

Another object of the invention is to provide a pivotally mounted control dial or operating member which has connecting means with adjacent louvers and which means are so proportioned and related to each other as to cause initial rotating movement of one louver at a greater speed than the initial rotating movement of the adjacent louver.

A further object of the invention is to provide in a register control mechanism a pivotally mounted operating dial or member in combina-

2
 tion with a link connected between the dial and each of the louvers to be operated wherein each link is of substantially the same length and is mounted on the dial the same distance from the center of rotation of the dial, the greater initial velocity of the one louver being obtained both through the arrangement of the direction of force which is caused to rotate the louver and through arranging properly the relative perpendicular distances from each link to the pivot for the respective louvers to which they are connected.

Other objects and advantages of the invention will become apparent upon reading the following description taken in conjunction with the accompanying drawing in which:

Fig. 1 is a vertical transverse sectional view through the frame of a register illustrating the control mechanism of the present invention in elevation and showing the louvers in closed position; and

Fig. 2 is a view similar to Fig. 1 but showing the louvers in open position.

The necessity of initially moving the leading edge of one louver of a pair which rotate in relatively opposite directions at a greater velocity than the adjacent edge of the other louver when these edges are in overlapping relation has been recognized heretofore but the mechanism suggested to accomplish this result has been relatively costly because of the numerous different specific parts involved. It has been proposed either that the links be made of different lengths; or that they be mounted on the operating member at unequal distances from the center of rotation of the member, all of which necessitates the manufacture of numerous different sized parts and assembling them in specific relationships to be sure that the proper link length is secured to the operating member at the proper location, all of which tends to increase the general cost of manufacture.

The present invention involves a greatly simplified construction wherein the links may be substantially the same length and are pivotally connected to the operating member at the same distances from the pivot thereof so that during the manufacture only one length of link is necessary and these links may be pivotally connected to either of the openings provided therefor in the operating member.

Referring now more particularly to the drawing, the register comprises a frame generally indicated by the numeral 1 which is of the usual form and includes the elongated side members 2

and ends 3. The sides and ends are flanged outwardly at their upper edges as shown at 4 to provide a support by which the frame may be suspended in the floor of a room. The frame itself has an open upper side 5 and an open lower side 6 for the passage of air therethrough when the louvers are in open position. It is understood that directional vanes may be provided in the upper portion of the frame if desired but such vanes have not been illustrated herein since they form no part of the present invention.

The particular register shown in the drawing for purposes of illustration is provided with two louvers 7 and 8. It is to be understood, however, that a greater number of louvers may be provided if desired and for a register having a larger opening therethrough in which case any suitable and well-known means may be provided for connecting every other louver together, wherefore a single control mechanism will operate all of the louvers simultaneously.

The louvers 7 and 8 are pivotally mounted by means of rods or pivot pins 9 and 10, respectively, suitably journaled in the ends of the frame and secured to the offset portions 11 and 12 between the longitudinal edges of the respective louvers. In the embodiment shown the louver 7 is mounted on its pivot to rotate in a clockwise direction to open position and the louver 8 is mounted on its pivot to rotate in a counterclockwise direction to open position. The louver 8 is provided with an offset 13 along the longitudinal edge thereof adjacent the inner edge of the louver 7 whereby the adjacent edges of the two louvers may overlap and form an effective seal against the passage of dust and dirt as well as heat therethrough when in closed position. The outer longitudinal edges of the respective louvers 7 and 8 contact the lower edges of the frame thereby limiting the closed movement thereof.

It will be evident that in order to assure the smooth operation of the louvers when they are moving to open position, as well as returning to closed position, it is necessary that the inner edge of louver 7 move upwardly at an initially greater speed or through a relatively greater arc than the inner edge of louver 8. As stated above, this result has been attained in the present instance by the use of a novel control mechanism wherein the parts thereof are substantially identical, it being merely necessary to position the parts relative to each other in such a way that the desired operation will result.

A dial or disk 14 constitutes the operating member for the two louvers 7 and 8. The dial or operating member 14 is pivotally mounted in the frame as at 15 between the pivots 9 and 10 of the louvers and at a substantial distance thereabove. The louver 7 is caused to rotate in a clockwise direction about its pivot 9 by means of a link 16 pivotally connected at one end thereof as at 17 to the operating member or dial 14. The other end of link 16 is pivotally connected as at 18 to an upstanding ear 19 secured to or formed integral with the louver 7 adjacent one end thereof. Thus far it will be evident that a counterclockwise rotation of the dial 14 will cause a movement of the link 16 toward the right exerting a force in a direction almost parallel to the plane of louver 7 which will cause the louver to rotate about its pivot 9. Since the pivotal connection 18 between the link 16 and the louver 7 is between the pivots 9 and

10 of the louvers, the direction of rotation of the louver 7 will be clockwise and it may be moved all the way to the position shown in Fig. 2.

The operating means for the louver 8 includes a link 20 pivotally connected by means of the pivot 21 at one end thereof to the dial or operating member 14. The opposite end of link 20 is connected by means such as the pivot 22 to an upstanding ear 23 secured to or formed integral with the louver 8 adjacent one end thereof. A counterclockwise rotation of the dial or operating member 14 will exert an angular downward force against the louver 8 to cause it to rotate about its pivot 10. Since, however, the pivotal connection 22 between the link 20 and the louver 8 is on the side of the pivot 10 therefore which is away from the pivot 9 for the louver 7, the direction of rotation of the louver 8 will be counterclockwise.

The links 16 and 20 are of substantially the same length and it will therefore be obvious that the cost of producing the mechanism embodying the present invention will be decreased since it will be unnecessary to produce links of different lengths. Furthermore, the pivot 17 of link 16 is the same distance away from the pivot 15 as the pivot 21 for the link 20. Therefore, when the dial is stamped and holes made for the reception of pivots 17 and 21, it makes no difference in assembling which of the links 16 or 20 is pivoted to pivots 17 or 21 because of the substantially identical lengths of the links and their same distances from the pivot 15 of the operating member 14.

It is still advisable, however, to position the various parts with respect to each other so that the leading inner edge of louver 7 will move faster or through a greater arc initially than the inner edge of louver 8. This result is accomplished by so positioning link 16 on the dial 14 and connecting to the louver 7 so that the perpendicular distance from the link 16 to the pivot 9 for louver 7 will be less than the perpendicular distance from link 20 to the pivot 10 of the louver 8. It is also necessary in the present construction that the perpendicular distances from both links 16 and 20 to the pivot 15, which is the center of rotation of the operating member 14, are the same. For purposes of illustration the perpendicular distance from the center line of the link 16 to the center of rotation of dial 14 has been indicated by "x." The perpendicular distance from the center line of link 20 to the center of rotation of dial 14 has been indicated by the letter "y." "x" and "y" are the same as shown in Fig. 1.

The perpendicular distance from an extension of the center line of link 16 to the center of pivot 9 for louver 7 is indicated as x' and the perpendicular distance from the extension of the center line of link 20 to the center of pivot 10 for louver 8 is indicated by y' . In the present instance these two distances are different, x' being less than y' so that upon the initial movement of the dial 14 the inner edge of louver 7 will move faster or through a greater arc initially than will the inner edge of louver 8, thus assuring the avoidance of any interference between the adjacent inner edges of the two louvers when moving from closed to open positions and when moving from open back to closed positions.

It will thus be evident that a counterclockwise rotation of the dial or member 14 will cause simultaneous rotation of the louvers 7 and 8 in relatively opposite directions from the closed

position thereof to open position without interference between the adjacent inner edges of the two louvers. Fig. 2 illustrates the position of the parts when the two louvers have been moved to vertical position or completely open. Suitable stop means (not shown) may be provided if desired to limit the opening movement of the two louvers.

From the foregoing it will be clear that the present invention embodies a departure from structures proposed heretofore where it was thought necessary to form the two links of different lengths and to position them on the operating member at different distances from the pivot of the operating member. To do so is more costly than the structure embodying the present invention where the parts may be interchangeable and more easily and quickly assembled.

Changes may be made in the form, construction and arrangement of parts from those disclosed herein without in any way departing from the spirit of the invention or sacrificing any of the attendant advantages thereof, provided, however, that such changes fall within the scope of the claims appended hereto.

The invention is hereby claimed as follows:

1. In a damper mechanism having a pair of louvers mounted for rotation in relatively opposite directions, in combination, a frame, a pair of louvers pivoted in said frame and having the adjacent edges thereof in overlapping relation when in closed position, an operating member for said louvers mounted for rotation at one end of said frame, a link pivotally connected at one end thereof to said member and at its other end to one of said louvers at a point thereon at one side of a plane passing through the center of rotation of said member and parallel to said louvers when in completely open position, and a second link pivotally connected at one end thereof to said member and at its other end to the other of said louvers at a point thereon at the opposite side of said plane passing through the center of rotation of said member, the proportions of the parts being such that in closed damper position the perpendicular distance from each said link to the center of rotation of said member is substantially the same.

2. In a damper mechanism having a pair of louvers mounted for rotation in relatively opposite directions, in combination, a frame, a pair of louvers pivoted in said frame and having the adjacent edges thereof in overlapping relation when in closed position, the pivot for each said louver being between the edges thereof, an operating member for said louvers mounted for rotation in said frame between the pivots for said louvers and at one side of a plane passing through the louver pivots, a first link pivotally connected at one end thereof to said member and at the other end thereof to one of said louvers between the pivots for said louvers, and a second link pivotally connected at one end thereof to said member and at the other end thereof to the other louver at a point thereon which is on the side of the pivot for said other louver away from the pivot for the first mentioned louver, the proportions of the parts being such that in closed damper position the perpendicular distance from each said link to the center of rotation of said member is substantially the same, and the perpendicular distance from a plane passing through the pivot points of said first link to the pivot of said first mentioned louver is

less than the perpendicular distance from a plane passing through the pivot points of said second link to the pivot for said other louver.

3. In a damper mechanism having a pair of louvers mounted for rotation in relatively opposite directions, in combination, a frame, a pair of louvers pivoted in said frame and having the adjacent edges thereof in overlapping relation when in closed position, the pivot for each said louver being located between the edges thereof, an operating disk pivotally mounted at substantially the center thereof between the pivots for said louvers and in said frame, a first link pivotally connected at one end thereof to said disk and at the other end thereof to one of said louvers at a point thereon between the pivots for said louvers, and a second link pivotally connected at one end thereof to said disk and at the other end thereof to the other louver at a point thereon which is on the side of the pivot for said other louver away from the pivot for the first mentioned louver, the proportions of the parts being such that in closed damper position the perpendicular distance from each said link to the pivot of said disk is substantially the same, and the perpendicular distance from a plane passing through the pivot points of said first link to the pivot of said first mentioned louver is less than the perpendicular distance from a plane passing through the pivot points of said second link to the pivot for said other louver.

4. In a damper mechanism having a pair of louvers mounted for rotation in relatively opposite directions, in combination, a frame, a pair of louvers pivoted in said frame and having the adjacent edges thereof in overlapping relation when in closed position, an operating member for said louvers pivotally mounted in said frame, a first link and a second link, both of said links being pivotally mounted on said member equal distances from the pivot of said member, said first link also being pivotally connected to one of said louvers at a point thereon between the pivots for said louvers, said second link being also pivotally connected to the other louver at a point thereon which is on the side of the pivot for said other louver away from the pivot for the first mentioned louver, the proportions of the parts being such that in closed damper position the perpendicular distance from a plane passing through the pivot points of said first link to the pivot of said first mentioned louver is less than the perpendicular distance from a plane passing through the pivot points of said second link to the pivot for said other louver.

5. In a damper mechanism having a pair of louvers mounted for rotation in relatively opposite directions, in combination, a frame, a pair of louvers pivoted in said frame and having the adjacent edges thereof in overlapping relation when in closed position, an operating member for said louvers pivotally mounted in said frame, a first link and a second link, both of said links being pivotally mounted on said member, said first link also being pivotally connected to one of said louvers at a point thereon between the pivots for said louvers, said second link being also pivotally connected to the other louver at a point thereon which is on the side of the pivot for said other louver away from the pivot for the first mentioned louver, the proportions of the parts being such that in closed damper position the perpendicular distance from said first link to the pivot of said first mentioned louver is less than the perpendicular distance from a

plane passing through the pivot points of said second link to the pivot for said other louver.
